(57) **CLAIM**

The ornamental design for a display screen or portion thereof having a graphical user interface with an abstracted visualization of an interactive data analysis tool as shown and described.

DESCRIPTION

FIG. 1 is a first embodiment of the display screen or portion thereof having a graphical user interface with an abstracted visualization of an interactive data analysis tool showing our new design; and,

FIG. 2 is a second embodiment thereof.

The broken lines showing the display screen or portion thereof (the rectangular box surrounding the graphical user interface) illustrate the article of manufacture. The remaining broken lines show elements of the graphical user interface. None of the broken lines form part of the claimed design.
